DESIGN FOR A BUCKET HANGER FOR LADDERS

Kendall S. Ewer, Cape May, N. J.

Application September 26, 1945, Serial No. 122,355

Term of patent 7 years

(Cl. D17—12)

To all whom it may concern:

Be it known that I, Kendall S. Ewer, a citizen of the United States, residing at Cape May, in the county of Cape May and State of New Jersey, have invented a new, original, and ornamental Design for a Bucket Hanger for Ladders, of which the following is a specification, reference being had to the accompanying drawing, forming part thereof.

Figure 1 is a perspective view of a bucket hanger for ladders showing my new design;

Fig. 2 is a front elevation of the bucket hanger shown in Fig. 1; and,

Fig. 3 is an end elevation thereof.

I claim:

The ornamental design for a bucket hanger for ladders, substantially as shown.

KENDALL S. EWER.
